UNITED STATES PATENT OFFICE

170,174

AUTOMOTIVE VEHICLE DRYING UNIT

James Vani and Albert J. Malpede, Chicago, Ill.,
assignors to Service Metal Fabricators, Inc.,
Chicago, Ill., a corporation of Illinois

Application March 18, 1953, Serial No. 24,070

Term of patent 14 years

(Cl. D49—1)

To all whom it may concern:

Be it known that we, James Vani and Albert J. Malpede, citizens of the United States, residing at Chicago, Illinois, have invented a new, original, and ornamental Design for an Automotive-Vehicle Drying Unit, of which the following is a specification reference being made to the accompanying drawings forming a part hereof:

In the drawings:

Fig. 1 is a front elevational view of an automotive vehicle drying unit embodying our new design;

Fig. 2 is a top plan view of the same;

Fig. 3 is a rear elevational view thereof; and

Fig. 4 is an end elevational view as seen from the right hand end in Fig. 1.

We claim:

The ornamental design for an automotive vehicle drying unit, substantially as shown.

JAMES VANI.

ALBERT J. MALPEDE.
